UNITED STATES PATENT OFFICE.

CHARLES S. C. ROCK, OF NEW YORK, N. Y., ASSIGNOR TO FRUIN & WALKER COMPANY,
A CORPORATION OF ILLINOIS.

DRAINAGE AND VENT FITTING.

1,165,127.

Specification of Letters Patent.

Patented Dec. 21, 1915.

Original application filed December 17, 1912, Serial No. 737,209. Divided and this application filed January 16, 1914. Serial No. 812,446.

To all whom it may concern:

Be it known that I, CHARLES S. C. ROCK, a subject of the King of Great Britain, and a resident of the city of New York, borough 5 of Manhattan, in the county and State of New York, have invented a new and Improved Drainage and Vent Fitting, of which the following is a full, clear, and exact description, this being a division of the Letters 10 Patent of the United States for a waste and vent system, No. 1,086,938, granted to me February 10, 1914.

The object of the invention is to provide a new and improved drainage and vent fitting designed to connect the soil pipe with the vent pipe and adapted to connect with bath tubs, sinks, water closets and other fixtures to be drained and vented, the arrangement being such that the plumber can 20 readily assemble the parts and make the desired connections so that proper drainage and venting is insured.

In order to accomplish the desired result use is made of a drainage and vent fitting, 25 comprising in a single-piece structure a soil pipe member and a vent duct member extending integrally from the said soil pipe member, the said vent duct member extending a distance above the said soil pipe member, the upper end of the said vent duct member being arranged at an angle for connection with the main vent pipe, and the 30 said vent duct member being provided with a lateral opening for drainage and venting 35 of fixtures.

A practical embodiment of the invention is represented in the accompanying drawings forming a part of this specification, in which similar characters of reference indicate corresponding parts in all the views.

Figure 1 is a plan view of the combined soil pipe, drainage and vent fitting as applied, the soil and vent pipes and the walls of the building being shown in section; Fig. 45 2 is a side elevation of the combined soil pipe, drainage and vent fitting provided with two vent ducts and a separate inlet for drainage, parts being in section; Fig. 3 is a side elevation of the combined soil pipe, drainage and vent fitting applied to a soil pipe and having a single vent duct and a drainage inlet; Fig. 4 is a similar view of the same showing three vent ducts forming integral portions of the soil pipe member and terminating in a single terminal; Fig. 5 is a 55 like view of the fitting provided with a single vent duct; Fig. 6 is a similar view of the same and showing the fitting with two vent ducts for water closet and bath connection and partly shown in section; and Fig. 7 is a 60 similar view of the same and showing the fitting with two vent ducts for connection with a closet and sink, the upper end of the vent ducts being shown in section.

In the form of my invention illustrated in 65 Figs. 1 and 2, use is made of a combined soil pipe, drainage and vent fitting having a soil pipe member A forming a portion of the soil pipe B. From one side of the soil pipe member A extend vent ducts C and D having 70 their upper ends leading to a common terminal E extending laterally and arranged for engagement with a vent pipe member G forming part of the main vent pipe H. The terminal E is preferably threaded and 75 screws into a correspondingly-threaded hub F on the vent pipe member G. The vent ducts C and D are provided intermediate 80 their ends and at any desired height with lateral openings I and J, of which the opening I is connected with a sink I' (see Fig. 1), while the opening J is connected with a water closet J' to drain the same and to provide the desired venting. The vent ducts C and D may be spaced apart but are preferably 85 a unitary structure, as indicated in Fig. 2.

From the side of the soil pipe member A extends a branch inlet K having a hub K' adapted to be connected by a pipe K² with 90 a fixture K³ which is vented to a hub L formed on the main vent pipe member G. For the purpose described use is made of a pipe H (see Fig. 1) from which leads a branch pipe N' to the fixture K³, and, if desired, other fixtures, for instance, a bath tub O, may be connected by a pipe O' with the pipe K for drainage purposes, and by a branch pipe O² with the pipe N. Other fixtures, such as a bath tub P and a water 100 closet Q, may be connected with a second combined soil pipe drainage and vent fitting arranged on a second soil pipe B', the said second fitting having on its vent ducts C and D a common terminal E connected by a pipe 105 R with the pipe N, it being understood that

the bath tub P connects by a pipe P' with the lateral opening I of the second fitting, and the water closet Q connects with the lateral opening J of this second fitting by a pipe Q'. By the arrangement described a single vent pipe H can be used for properly venting a large number of fixtures which drain into the soil pipes B and B'.

In the modified form shown in Fig. 3, the 10 combined soil pipe, drainage and vent fitting consists of a soil pipe member A' forming part of the main soil pipe B², and from one side of the said member A' extends integrally and upwardly a vent duct D' having a lateral threaded terminal E' for engagement with the main vent pipe member G. The duct D' is provided with a lateral opening J² for connection with a water closet, and from the side of the member A' extends a drainage inlet K⁴ having a hub K⁵ for connection with a fixture to be drained, the same as above described in reference to the drainage inlet K and its hub K'.

In the form shown in Fig. 4, the soil pipe member A² forms a portion of the soil pipe B³ and is provided with integral vent ducts C', D² and S, all leading to an integral lateral terminal E² arranged for connection with the vent pipe member G. The vent duct C' is provided with a lateral opening I² for connection with a sink, the duct B² is provided with a lateral opening J³ for connection with a water closet, and the vent duct S is provided with a lateral opening S' for connection with a bath tub or similar fixture.

In the simplest form of my invention as shown in Fig. 5, the soil pipe member A³ forms a part of the soil pipe B⁴ and is provided at one side with an integral upwardly extending vent duct D³, the lateral terminal E³ of which is adapted to connect with the vent pipe member G. The vent duct D³ is provided with a lateral opening J⁴ for connection with the water closet.

In the form shown in Fig. 6, the soil pipe member A⁴ forms part of the main soil pipe B⁵, and from the said member A⁴ extends the vent ducts D⁴ and S² leading to a common terminal E⁴ arranged for connection with the vent pipe member G. The duct D⁴ is provided with a lateral opening J⁵ for connection with a water closet, and the lateral opening S³ in the duct S² is arranged for connection with a bath tub.

In the form shown in Fig. 7, the soil pipe member A⁵ forms part of the soil pipe B⁶ and is provided with vent ducts C² and D⁵ having a common terminal E⁵ for connection with the vent pipe member G. The vent duct pipe C² is provided with a lateral opening I³ for connection with a sink, and the vent duct D⁵ is provided with a lateral opening J⁶ for connection with a water closet.

It is understood that by the arrangement described the lateral openings in the vent ducts may be at one side or the other according to the location of the fixtures to be drained and vented. It will further be 70 noticed that the lateral openings for fixtures may be at any point in the height of the vent ducts and denote the points at which the functions of wasting and venting are separated, venting operating upwardly 75 and wasting downwardly.

The fitting shown and described can be cheaply manufactured and arranged to suit existing conditions, and serves to enable the plumber to readily make the proper connection with the fixture to be drained and vented.

It will be understood that by the construction described there is, in case of settlement of one of the main pipes B or H 85 with reference to the other, less likelihood of a rupture of the joint and consequent leakage of gases. It will further be noticed that by providing the vent ducts with lateral connection a bracing action is provided by 90 tending to prevent a relative movement of one of the main pipes B or H with reference to the other.

Although various forms of my invention have been shown and described I do not 95 limit myself to the same as it is evident that under the varying conditions under which plumbing systems are installed, different forms may be necessary.

Having thus described my invention, I 100 claim as new and desire to secure by Letters Patent:

1. A fitting of the character described, comprising in a single-piece structure, a soil pipe member adapted to form a portion of the soil pipe, and a vent duct extending integrally from the side of the said soil pipe member, the said vent duct ranging in a plane in which lies the axis of the said soil pipe member, the said vent duct extending 110 a distance beyond the end of the said soil pipe member, the terminal of the said vent duct extending laterally and being threaded for connection with a threaded part on a main vent pipe, and the said vent duct being 115 provided intermediate its ends with lateral openings for connection with fixtures to be drained and vented.

2. A drainage and vent fitting comprising in a single-piece structure a soil pipe member and a vent duct member extending integrally from the said soil pipe member, the said vent duct member extending in a plane in which lies the axis of the said soil pipe member, the said vent duct extending a distance beyond the end of the said soil pipe member, the terminal of the said vent duct member being arranged at an angle for connection with a main vent pipe and the said vent duct member being provided with a 130

lateral opening for drainage and venting of a fixture.

3. A drainage and vent fitting, comprising in a single-piece structure a soil pipe member and a vent duct member extending integrally from the said soil pipe member, the said vent duct member extending a distance beyond the end of the said soil pipe member, the terminal of the said vent duct member extending laterally at an angle and being threaded for connection with a threaded part on a main vent pipe, and the said vent duct member being provided with a lateral opening for drainage and venting of a fixture.

4. A drainage and vent fitting, comprising in a single-piece structure a soil pipe member and a vent duct member extending integrally from the said soil pipe member, the said vent duct member extending a distance beyond the end of the said soil pipe member, the terminal of the said vent duct member being arranged at an angle for connection with a main vent pipe and the said vent duct member and the said soil pipe member being provided with lateral openings for drainage and venting fixtures.

5. A drainage and vent fitting, comprising in a single-piece structure a soil pipe member and a plurality of vent duct members extending integrally from the said soil

pipe member, the said vent duct members having a common terminal a distance extending beyond one end of the said soil pipe member, the terminal of the said vent duct members extending laterally at an angle and being arranged for connection with a main vent pipe, and the said vent duct members being provided with lateral openings for drainage and venting of fixtures.

6. A drainage and vent fitting, comprising in a single-piece structure a soil pipe member and a plurality of vent duct members extending integrally from the said soil pipe member, the said vent duct members having a common terminal a distance beyond the said soil pipe member, the terminal of the said vent duct members extending laterally at an angle and being arranged for connection with a main vent pipe, and the said vent duct members and the said soil pipe member being provided with lateral openings for drainage and venting of fixtures.

In testimony whereof I have signed my name to this specification in the presence of two subscribing witnesses.
